UNITED STATES PATENT OFFICE.

JULIAN A. GILES, OF OSWEGO, NEW YORK, ASSIGNOR TO ALBERT N.
RADCLIFFE, OF SAME PLACE.

TUBE-EXPANDER.

SPECIFICATION forming part of Letters Patent No. 361,504, dated April 19, 1887.

Application filed January 27, 1887. Serial No. 225,629. (No model.)

To all whom it may concern:

Be it known that I, JULIAN A. GILES, of Oswego, in the county of Oswego, in the State of New York, have invented new and useful 5 Improvements in Tube-Expanders, of which the following, taken in connection with the accompanying drawings, is a full, clear, and exact description.

This invention consists in a novel construction of a tube-expander, which has the expanding-rollers sustained in a rigid head or body and held normally in proximity to the axis of said head or body, as hereinafter more fully described, and specifically pointed out 15 in the claims.

The invention is fully illustrated in the annexed drawings, wherein Figure 1 is a side view of my improved tube-expander. Fig. 2 is an end view of the same. Fig. 3 is a longitudinal section on line *y y*, Fig. 2; and Fig. 4 is a transverse section on line *x x*, Fig. 1.

Similar letters of reference indicate corresponding parts.

B represents the expander head or body, 25 consisting of a rigid annular metallic block having an axial eye, *a*, for the reception of the usual tapering mandrel, A, and radial slots *b b*, through which the expanding-rollers *r r r* are extended.

30 At about midway the depth of the body B the aforesaid rollers are formed with circumferentially-reduced journals *c*, by which they are journaled on keepers *d d d*, consisting of blocks arranged in mortises *e e e*, extending through to the periphery of the body, said keepers being adapted to slide radially toward and from the center of the body B, and when at their extreme inner position the outer portions of the keepers are flush with the face of

35 a circumferential groove, *g*, in the exterior of the body B. In this groove is placed a spring-band, *f*, which encompasses the body B and crowds the keepers *d d d* inward, and thus sustains the rollers *r r r* normally in proximity to the axis of the body B and in proper position to allow the protruding ends of said rollers to be introduced into the end of the tube to be

expanded. When this is effected, the mandrel A is introduced between the rollers and forced inward until the rollers are caused to 50 press against the interior of the tube. Then by revolving the mandrel the rollers *r r r* receive rotary motion by their frictional hold on the mandrel, and in traveling around the interior of the tube, while subjected to outward pressure from the mandrel, the tube becomes expanded and tightened in the flue-sheet. 55

Having described my invention, what I claim as new, and desire to secure by Letters Patent, is—

1. In combination with the expanding-mandrel, the expander-body having an axial eye and radial slots, the expanding-rollers extending through said slots, keepers seated movably radially in the expander-body and bearing against the sides of the respective rollers, and a spring arranged to crowd the keepers toward the axis of the expander-body, as set forth.

2. In combination with the expanding-mandrel, the expander-body having an axial eye, radial slots extending from said eye, an external circumferential groove and mortises extending from said groove toward the axis of the expander-body and in the lines of the 75 radial slots, the expanding-rollers extending through said slots and formed with circumferentially-reduced journals inside of the expander-body, keepers sliding in the mortises of the body and provided with bearings corresponding to the journal portions of the rollers, and a spring encompassing the expander-body in the external groove thereof, substantially as described and shown.

In testimony whereof I have hereunto signed 85 my name and affixed my seal, in the presence of two attesting witnesses, at Oswego, in the county of Oswego, in the State of New York, this 22d day of January, 1887.

JULIAN A. GILES. [L. S.]
